ATTORNEY.

UNITED STATES PATENT OFFICE

WILLIAM D. HINCHEY, OF NEW YORK, N. Y.

RAZOR BLADE HOLDER

Application filed May 14, 1930. Serial No. 452,245.

This invention relates to razor blade holders for use in sharpening or honing double edged blades of the type having holes or grooves whereby they are held in position on the razor.

The holder is intended to be used in connection with a sharpener or hone having a concave face of semi-circular shape upon which face the blade is sharpened. The sharpener is preferably made of a block of glass.

One of the objects of the invention is to provide a holder which is so designed that no part of the holder comes between the blade and the face of the sharpener, thus presenting the full extent of both edges of the blade to the sharpening action of the glass block or hone.

Another object is to provide the holder with loose positioning pins, which pins, when the holder is held face down on the sharpening block, drop by gravity to hold the blade in position but without exerting any pressure on the face of the sharpening block.

Further objects of the invention will appear from the following description thereof, reference being had to the accompanying drawing, illustrating a preferred embodiment of the device, in which:

Fig. 1 is a top view of the holder,

Fig. 2 is an enlarged vertical section of the holder with the handle portion broken away, taken on the line 2-2 of Fig. 1.

Fig. 3 is a sectional view, taken on the line 3-3 of Fig. 4, showing the holder as it is positioned on the sharpening block prior to sharpening the razor blade, and

Fig. 4 is a rear elevational view thereof.

Referring now to the drawing, 1 indicates in general the razor blade holder which comprises a handle portion 2 and a hollow portion 3. The portion 3 has a flat upper surface 4 faced with a strip of leather 5 upon which the razor blade 15 rests. The leather facing is preferably so attached that it may be easily removed and replaced when desired. Pins 6, having enlarged heads 7, extend upwardly from the interior of the hollow portion 3 through holes formed in

its upper surface 4 and through the leather strip, the holes being slightly larger than the diameter of the pins to allow the pins to drop freely by gravity, for the purpose hereinafter described, when the holder is held face downward. The pins are so located as to register with the holes or grooves of the usual type of double-edged blade.

The pins 6 locate the blade on the holder and it is maintained in place thereon, when carrying the blade to or from the sharpener, by means of a slide 8, which engages over an inner end portion of the blade. The slide is carried on two rods 9 which are movable supported in the lugs 10 of the holder and it is normally held in forward position by means of springs 11.

In using the device the blade to be sharpened is placed on the holder which is then presented, face downward, to the concave face 12 of the sharpening block or hone 13 with the slide 8 abutting against the straight front edge 14 of the block. The holder is then pressed inwardly toward the block so as to move the slide 8 back and to release the blade from engagement therewith, thereby presenting the entire blade to the sharpener. The holder is now moved up and down along the face of the block to sharpen the edges of the blade. This movement may either be a straight up and down one, or a slightly diagonal movement. The angle which the edges of the blade make with the concave face of the sharpener depends on the amount of downward pressure applied to the holder.

When the blade is in sharpening position on the block, the pins 6 will drop by gravity downward towards the face 12 of the sharpener and thus serve to maintain the blade in proper relation to the holder. As the pins are slightly smaller in diameter than the holes through which they extend there might be some slight sideplay of the blade during the sharpening movement but this is counteracted by the provision of the leather strip 5 which acts frictionally to hold the blade firmly in place on the holder. After the sharpening operation is completed the holder is moved slightly away from the front of the block 13 permitting the slide 8 to re-

engage the blade so that the blade may be conveniently picked up and lifted off the sharpener.

It will be observed that during the sharpening operation the slide is held in retracted position so that no part of the holder comes between the blade and the sharpener block. Furthermore, the provision of the loose pins 6 permits of varying the angle of contact of 10 the blade-edges with the face of the sharpener because, as the pins are loose, they will automatically adjust themselves to the variations in vertical distance between the faces of the holder and the block caused by application of more or less downward pressure on the holder.

It is to be understood that modifications in the arrangement, shape, and construction of the parts of the device herein described and 20 illustrated may be made without departing from the scope of the invention.

What I claim is:—

1. A holder for use in sharpening double-edged safety razor blades comprising a handle portion and a hollow portion having a flat upper surface upon which the blade rests, blade-positioning pins having enlarged heads mounted in the hollow portion and projecting upward loosely through openings in the face of said portion, said pins being adapted to drop by gravity when the holder

is held face downward, and a spring pressed slide engageable with and disengageable from the blade to hold or release the same.

2. A razor blade holder of the character described comprising a handle portion and a hollow portion having a flat upper surface faced with leather upon which the blade rests, blade-positioning pins having enlarged heads mounted within the hollow portion of the holder and projecting upward loosely through openings in the upper surface and the leather facing of the holder, said pins being adapted to drop by gravity when the holder is held face downward, and a spring pressed slide mounted on the holder to engage over a portion of the blade, said slide being disengaged from the blade during the operation of sharpening the latter.

3. A razor blade holder of the character described comprising a handle portion and a blade-supporting portion, having a surface upon which the blade rests, blade-positioning pins mounted on said blade-supporting portion, and projecting upward loosely through openings in the face thereof, said pins being adapted to drop by gravity when the holder is held face downward, and a spring pressed slide mounted on the holder and engageable with the blade.
